UNITED STATES PATENT OFFICE.

HORACE SEE, OF NEW YORK, N. Y.

DESIGN FOR A BED-PLATE FOR STEAM-ENGINES.

SPECIFICATION forming part of Design No. 28,103, dated December 28, 1897.

Application filed August 25, 1897. Serial No. 649,535. Term of patent 14 years.

To all whom it may concern:

Be it known that I, HORACE SEE, of the city, county, and State of New York, have invented and produced a new and original 5 Design for a Bed-Plate for Steam-Engines, of which the following is a specification.

Figure 1 is a top view, and Fig. 2 is an end view, of a bed-plate exhibiting my design.

The body of the plate is in the form of a 10 quadrilateral frame A, having two cross-bars F G and three intervening openings C D E. The corners B of the frame are rounded. From one side of the frame extend projections H and I, having flat flanged upper surfaces J. A smaller projection may appear 15 also at K, and this projection is also provided with a flat upper surface J. In the frame A and cross-bars F G are recesses L, exposing a concave interior. The concavities M are disposed in line longitudinally the frame. Also, in one end of the frame and cross-bars F G are recesses N, which can be concave, 20 and the concavities O are also in line parallel to the concavities M. The recesses L N are

essential to my design, but the concavities 25 M O are not.

The frame A is provided with a bottom flange P. In the side walls of the frame there may be openings, such as Q, but these are not essential to my design.

On the right-hand side of the frame A are three circular projections R S T. The upper sides of these projections, as shown in Fig. 2 at U, are inclined, and their level is shown in Fig. 2 as below that of the flanges J.

Below the recess O there may appear in the frame and cross-bars an opening V, and below the recess L may appear openings W, but these openings V W are not essential to my design.

I claim—

The design for a bed-plate for a steam-engine, substantially as herein shown and described.

HORACE SEE.
